ABSTRACT

An automatic spool feeding method and apparatus for automatic winders. Spools are properly arranged and held in a spool supply means on poles through the inner diameter portions of the core tubes of the spools. Spool transfer means transfers a fixed number of spools from the poles of said spool supply means to a spool holding line, which spool holding line is circulatable. Spool feed means receives the spools from the spool holding line and feeds them to the pegs of an automatic winder.

AUTOMATIC SPOOL FEEDING METHOD AND APPARATUS FOR AUTOMATIC WINDING MACHINE

The present invention relates to an automatic spool feeding method and apparatus for automatic winding machines. More particularly, it relates to a method and apparatus whereby open-end spinning machine-produced spools are automatically fed to an automatic winding machine efficiently and accurately without requiring any manual operations. Such spools are produced by winding yarn on a core tube in an open-end spinning machine.

Open-end spinning machine-produced spools might be used directly for weaving and knitting purposes without being rewound by a winder. However, correction of the amount of spooled yarn, formation of cone-shaped cheeses or cleaning of yarn makes rewinding necessary. As is already known, however, spools produced by an open-end spinning machine have a shape considerably different from that of full bobbins produced by the conventional ring spinning machine, and many of such spools are shaped in the form a stub cylinder with a diameter 2-3 times as large as its height. As a result, such spools cannot be treated by the known automatic winder designed for use with spindle-shaped full bobbins produced by the conventional ring spinning machine. That is to say, in the conventional automatic winding machine, when full bobbins are to be inserted onto the pegs of the winding units, they undergo positional control effected by a chute having a guide designed on the basis of the outer diameter of a spindle-shaped full bobbin and are then transferred to the pegs. If the above-mentioned known technique is applied to said spools having the form of a stub cylinder, the insertion of spools onto the pegs will fail in almost all cases since the spools fall with their axes assuming a horizontal position or since they form a bridge when they are falling. Moreover, said spools often have outer yarn diameters which differ from each thus in the outer diameter of the windings of yarn, thus making the positional control of spools impossible.

An object of the present invention is to provide a method and apparatus for automatically feeding spools to an automatic winder, which method and apparatus are not affected by the differences in the outer diameter of spools, characterized in that a large number of spools are properly oriented and held in position by the use of the inner diameter portions of their core tubes and that the reception and delivery of spools and subsequent transfer thereof are effected on the basis of the inner diameter portions of the core tubes of said spools.

Another object of the invention is to provide an automatic spool feeding method which, when spools properly oriented and held in position by the use of the inner diameter portions of the core tubes are to be received and delivered on the basis of the inner diameter portions of the core tubes of said spools, carries out the transfer operation while ascertaining whether or not the spools have been correctly received and delivered.

A further object of the invention is to provide an apparatus whereby cheese-shaped spools produced by an open-end spinning machine are automatically, successively and individually fed to an automatic winder for rewinding purposes.

An automatic spool feeding apparatus according to the invention comprises a plurality of poles arranged at fixed intervals, spool supply means for placing a number of spools onto said poles with the poles through the core tube hollow portions to properly orient and hold them in position, spool transfer means for transferring a fixed number of spools from said spool supply means to spool holders, said spool holders being travelable, and spool feed means for receiving spools from said spool holders at a predetermined position and feeding them to the pegs of an automatic winder.

The present method and apparatus will now be described in more detail with reference to the accompanying drawings illustrating a concrete example thereof. In the drawings;

FIG. 1 is a schematic plan view showing the layout of the present apparatus;

FIG. 2 is a plan view of a main apparatus body;

FIG. 3 is a longitudinal section of carriage positioning means;

FIG. 4 is a plan view of the carriage positioning means of FIG. 3;

FIGS. 5A and 5B are a longitudinal section and a cross section, respectively of jack means shown in FIG. 4;

FIG. 6 is a front view of means for supplying spools, which means takes the place of a carriage;

FIGS. 7 and 8 are a side view and a plan view, respectively, of the means of FIG. 6;

FIG. 9 is a front view of spool transfer means;

FIG. 10 is a fragmentary side view of the spool transfer means;

FIGS. 11a, b and c are electrical wiring diagrams for the spool transfer operation;

FIG. 12 is a front view of spool holding means;

FIG. 13 is a longitudinal section of a spool holder;

FIG. 14 is a perspective view of the spool supplying means;

FIGS. 15 and 16 are a front view and a side view, respectively, of a swing arm and a push-out lever;

FIG. 17 is a perspective view showing the operation of a presser lever in releasing a spool;

FIG. 18 is a perspective view showing a reciprocating mechanism for a slide shaft;

FIG. 19 is a perspective view showing a mechanism for rotating the slide shaft;

FIG. 20 is a perspective view showing a rotating mechanism for a suction nozzle for picking up the yarn end from a spool;

FIG. 21 is a perspective view showing the construction of a peg of a winder;

FIGS. 22 A-D are schematic explanatory views showing the transfer operation of a spool to a peg of the winder, wherein FIG. A shows a condition in which the peg is stopped to receive a spool, FIG. B shows a condition in which the peg is tilted by the action of the slide shaft, FIG. C shows a condition in which a spool is transferred from the peg of a swing arm and FIG. D shows a condition in which the transfer of the spool is completed and the peg is returned to its normal position; and

FIG. 23 is an electrical wiring diagram for ascertaining the completion of the spool transfer operation shown in FIG. 22.

According to the invention, an apparatus for feeding spools to an automatic winder comprises carriage positioning means whereby a specially constructed carriage for conveying spools from an open-end spinning machine is stopped at a predetermined position in front of a main apparatus body together with spools carried thereon, spool transfer means for withdrawing spools from the thus positioned carriage, a circulatable spool holding line for holding the withdrawn spools, spool feed means for receiving the spools from the spool holding line and feeding them to the pegs of an automatic winder and knotter means for knotting together the yarn end of a fed spool and the yarn end of a cheese being wound. As for the knotter means, a known device is employed in the invention and therefore the description of the construction thereof will be omitted.

In FIG. 1, the character E denotes a main apparatus body; F, spool supply means; G, spool transfer means; H, a spool holding line; I, knotter means; J, spool feed means; K, a winder; L, a winding unit; and M denotes means for detecting the presence or absence of the remnants of yarn on spools placed onto the pegs N of the winding units.

In FIG. 2, various mechanisms for driving the components of the present apparatus such as spool feed means G, knotter means I and spool feed means J are collectively shown. Like reference numerals will be used to indicate like parts throughout the Figures.

FIGS. 3-5 shown an example in which a carriage is used as the spool supply means F. Means for positioning said carriage is also shown therein.

Such carriage 21 has several poles erected thereon. It is so arranged that a number of spools 28 from an open-end spinning machine are placed onto the poles 26 of said carriage and that the carriage is then guided to a predetermined position relative to the main apparatus body E and stopped there, where the spools 28 are then fed to the spool holders P of the spool holding line H by the spool transfer means G. The main apparatus body E is provided with a positioning mechanism for setting the position of the carriage 21. The positioning mechanism is installed in a pit 1 formed below the level of a floor surface 0 and has a base 2 on which are disposed an electric motor 3 and four jack means 13 each having a screw shaft 10; said motor 3 and jack means 13 being interconnected through sprockets 4, 6, 7, 8 and 9 and an endless chain 5. The threaded shaft 10 has a frustoconical head 11 and an axially extending groove 12 in which the front ends of set screws 14 are fitted, as shown in FIGS. 4 and 5 so that the shaft is permitted to move only upwardly and downwardly. The sprockets 6, 7, 8, 9 and threaded shafts 10 are threadedly engaged. When a clockwise rotation as viewed in FIG. 4 is imparted to the sprockets, the shafts 10 will be moved upwardly, and when a counter-clockwise rotation is imparted thereto, they will be moved downwardly. The numeral 20 denotes a microswitch for limiting the downward movement of the shaft 10. The pit 1 has a cover 15 flush with the floor surface 0, said cover being formed with holes 16 through which the shafts 10 can pass when moving upwardly, said cover being provided with a hinge 18 constantly urged in an opening direction by a spring 17. The numeral 19 denotes a microswitch having contacts are operated by the opening and closing of the hinge 18. The numeral 22 denotes a wheel caster.

The bottom surface of the carriage 21 is provided with wheels 25 and also with four receivers 24 each having a recess 23 for engagement with the head 11 of one of said four threaded shafts 10. The top surface of 5 the carriage 21 is provided with a plurality of poles 26 erected thereon at equal intervals and a large number of spools 28 produced by an open-end spinning machine are placed onto said poles 26, as shown in FIG. 3. On the lower portion of each of said poles 26, a 10 spool receiving plate 29 is disposed so as to be slideable along the pole 26. Spool raising frame 27 is disposed between the receiver plates 29 and the top surface of the carriage 21 with said poles 26 being positioned therebetween, the frame 27 being movable upwardly and downwardly along vertical slots (not shown) formed in the lateral walls 21' of the carriage 21.

In the above, as the spool supply means F there has been shown an example in which poles 26 for carrying spools 28 thereon are erected on a carriage 21, but as 20 an alternative there may be provided an arrangement as shown in FIGS. 6-8 wherein a number of poles are erected in a predetermined position in front of the main apparatus body so as to be circulatable and spools 28 25 conveyed thereto by a conventional pushcart are inserted on the side opposite to the side where the transfer means G is positioned, and said poles are then caused to be circulated to feed the spools to the spool holding line H. In this case it takes time to transfer the spools 28 from the pushcart to the poles 26, but there is 30 the advantage that the positioning mechanism in the pit 1 for the carriage 21 becomes unnecessary. FIGS. 9-11 show the spool transfer means G withdrawing the spool 35 28 from the carriage 21. The spool transfer means G serves to transfer the spools 28 positioned on said poles 26 to the spool holders P of the spool holding line H and the means G comprises lifts 38 and 39 adapted to be moved upwardly and downwardly by starting an electric motor 30. The spool transfer means G is shown 40 concretely in FIGS. 2, 9 and 10. The lifts 38 and 39 are substantially horizontally fixed to endless chains 31 and 37 which interconnect sprockets 33 and 35 fixed on the opposite ends of a shaft 34 disposed horizontally in the main apparatus body E, a motor sprocket 32 and a 45 rotatably mounted sprocket 36. The upward and downward movements of the lifts are effected by the forward and reverse rotations of the motor 30 while the lifts are controlled by the guides 41, 42.

One lift 39 is provided with a switch cam 43 which, 50 when the lift is moving upwardly and downwardly, abuts against a lift upward-movement controlling microswitch 44 disposed at an upper position relative to the guide 42 and a lift downward-movement controlling microswitch 45 disposed at a lower position, 55 thereby controlling the upward and downward movements of the lifts, and which cam 43 also actuates another microswitch 46 provided between said microswitches 44 and 45 for counting the number of upward and downward movements of the lifts 38, 39.

The circulatable spool holding line H shown in FIGS. 12 and 13 will now be described. The power of a motor 50 provided on a machine frame 40 (FIG. 2) is transmitted by endless chains 51 through sprockets 52 and 53 to an upper spool feed cam shaft 54 and to a knotter cam shaft 55. Solenoid clutches 57 and 58 are provided 60 between the sprockets 53 and the spool feed cam shaft 54 and between the sprockets 52 and the knotter cam

shaft 55, respectively. Further, solenoid brakes 59 and 58 are provided at the other ends of the spool feed cam shaft 55 and knotter cam shaft 54, respectively. The solenoid clutches 57, 56 and the solenoid brakes 58, 59 are so interrelated that when the solenoid clutches are on, the solenoid brakes are off and as soon as the solenoid clutches are turned off, the solenoid brakes are caused to operate. Even in normal waiting conditions the motor 50 is rotating but the clutches 57 and 56 remain disengaged. The spool feed cam shaft 54 rotatably supported by the machine frame 40 has fixed thereto a bevel gear 60 for imparting rotation to the spool holding line H disposed thereabove, and also has fixed thereto microswitch actuating cams 61, 62 and 63 and spool feed means actuating cams 64, 65, 66, 67, 68 and 69. The bevel gear 60 is adapted to impart rotation to an upper sprocket 72 through a vertical shaft 71 having a bevel gear 70 meshing therewith. A chain 74 imparting rotation to a Geneva crank 73 is entrained around said sprocket 72, said Geneva crank 73 being engaged with a Geneva wheel 75 fixed on the same shaft as sprocket wheels 76. Carrier chains 79 to which the spool holders P are threadedly secured are entrained around the sprocket wheels 76, 77 and 78. By intermittently moving said chains 79, the spools 28 are transferred to the spool feed means J to be later described.

The spool holders P are suspended over the spool insertion poles 26 of the carriage 21 in a position where they are opposed to said poles 26. The upward movement of the lifts 38 and 39 described above causes the spools 28 to be transferred from the poles 26 to the holders P thereabove. The numerals 80, 81, 82, 83 and 84 denote microswitches for ascertaining and detecting that the spools 28 have been transferred onto the holders P.

The relation between the spool feed means G and the spool holding line H will not be described. It is so arranged that when all of the microswitches 80, 81, 82, 83 and 84 detect that the top stage spools on the spool insertion poles 26 have been transferred to the spool holders P as the lifts 38 and 39 are moved upwardly to raise the spool raising frames 27, the power source for the motor 30 is changed over so that the lifts 38 and 39 begin to move downwardly. Of the five microswitches 80, 81, 82, 83 and 84, the microswitch 84 at the left-hand extremity is a two-contact switch and also detects when the five spool holders P above poles 26 are empty after the five spools held on the five spool holders P after a transfer operation have been moved to the left as viewed in FIG. 1 to be successively transferred to the spool feed means J, and the microswitch again issues an upward movement command to the lifts 38 and 39. It is so arranged that if the lifts 38 and 39 are moved upwardly with no spools present on the carriage, the switch cam 43 acts on the lift upward-movement controlling microswitch 44 to rotate the motor 30 in the reverse direction to immediately lower the lifts 38 and 39 and the switch cam 43 acts on the downward movement controlling microswitch 45 to stop the motor 30.

The concrete construction of the spool holders P for holding the spool 28 raised by the lifts 38 and 39 and transferred to the feed means J to be later described is shown in FIG. 13.

Thus, the reference numeral 90 denotes a switch lever pivotable around the axis of a pin 91, which switch lever is constantly urged in a counter-clockwise direction around the axis of the pin 91 by a spring 92 and, in the Figure, the lever is shown in its position prior to the transfer of the spool 28 in which a claw 93 at the front end is engaged with a fixing pin 100 fixed to a holder shaft 94. The holder shaft 94 is fitted in a tube body 96 fixed to a main body 95 and is constantly urged upwardly by a compression spring 97. The holder shaft 94 has a head body 98 carried on the lower end thereof and a ring body 99 made of rubber is provided between the head body 98 and the main body 95. When the spool 28 is raised by the upward movement of the lifts 38 and 39 and transferred onto the holder P, the switch lever 90 is pushed up by the upper surface of the spool 28 so that said lever 90 is turned clockwise around the axis of the pin 90. As a result, the claw 93 is disengaged from the fixing pin 100 and the holder shaft 94 and head body 98 are moved upwardly by the restoring action of the compression spring 97 so that the ring body 99 is strongly compressed axially between the head body 98 and the main body 95 and is deformed so that its outer periphery bulges outwardly into close contact with the inner-surface of the core tube of the spool 28, whereby the spool is held. Conversely, when the inserted spool 28 is to be released, this is achieved by pushing down the upper end of the holder shaft 94 to cause the head body 98 to move away from the main body 95 and free the ring body 99 so that the spool 28 falls under its own weight and at the same time the claw 93 of the lever 90 is engaged with the fixing pin 100 so that the upward movement of the holder shaft 94 is stopped and the condition shown in FIG. 13 is established.

The spools 28 held by the spool holders P are transferred to the spool feed means J during the intermittent movement of the carrier chains 79 caused by the Geneva wheel 75. The spool feed means J is constructed in the manner shown in FIGS. 14, 15 and 16. However, the transfer of spools 28 from the spool holders P of the spool holding line H to the spool feed means J is effected by the mechanism shown in FIG. 17. That is to say, the cam 64 on the spool feed cam shaft 54 to which rotation is transmitted from the motor 50 is connected with a presser lever 107 through a lever 102 fitted on a counter shaft 101 and through rods 103 and 104. The top of the holder shaft 94 of the spool holder P holding the spool and stopped below the end of the presser lever 107 is opposed to the presser lever 107 and when there is a command for the spool to be discharged, the cam 64 is rotated to cause the presser lever 107 to push down the holder shaft 94 to overcome the spool holding force of the spool holder P as described above so that the spool falls onto the swing arm 118 of the spool feed means J to be later described.

The spool feed means will now be described with reference to FIGS. 2 and 14-23. The spool feed means J serves to receive fresh spools from the spool holding line H and feed them to the pegs N of the winding units L of the automatic winder K. The cam 65 on the spool feed cam shaft 54 driven from the motor 50 shown in FIG. 2 serves to advance a slide shaft 110 toward the peg N of a winding unit K through the intermediary of a lever fitted on a counter shaft 108, said slide shaft 110

being adapted to be driven for rotation by a pinion 113 on said shaft 110 meshing with a sector gear 114 (see FIG. 18).

As shown in FIG. 14, the swing arm 118 for transferring the spool 28 to the winder peg N is pivotally mounted on a shaft 120 fixed to a bracket 119. The lower extension 121 of the swing arm 118 is connected to a swing lever 116 through a link 117. The swing lever 116 is operatively connected by shaft 108 to a swing lever 115 which is in contact with the cam 66 on the above-mentioned spool feed cam shaft 54. The parts are arranged so that when the swing lever 116 is turned counter-clockwise as viewed in FIG. 16 by the rotation of the cam 66, the swing arm 118 is turned in the same direction around the axis of the shaft 120.

As shown in FIGS. 14 and 15, the swing arm 118 carries at its free end remote from extension 121 a pivotable inverted L-shaped arm 122 having a spool receiving peg R mounted on one end thereof. The other end of the arm 122 is connected to a rod 123 pivotally mounted on fixed part, whereby when said swing arm 118 is turned from a vertical to a horizontal position, the inverted L-shaped arm 122 is also turned so that the peg R which has been positioned axially of the swing arm 118 is displaced in a direction perpendicular to the axis of the swing arm 118 so as to be brought into opposed relation to the peg N of the winding unit K thereby to make possible the transfer of the spool. One end of a swing lever 125 pivotable around the axis of the counter shaft 101 is pressed against the cam 67 on the spool feed cam shaft 54 and the other end of said swing lever 125 is connected through a link to one end of an L-shaped lever 127 pivotable on a fulcrum 126 on the machine frame 40. The other end of the L-shaped lever 127 is fork-shaped and is adapted to press one end 129 of a spool push-out lever 128 when it is turned. The numeral 130 denotes a restoring spring for the spool push-out lever 128. The front end of the push-out lever 128 is fork-shaped to hold the peg R on the top of the swing arm 118 in the space within the fork so as to push the spool on said peg R toward the peg N of the winding unit L.

The cam 68, which turns a suction nozzle 131 for the automatic knitter means, is operatively connected with a suction pipe 133 through a swing arm 132 supported on the counter shaft 101. The swing movement of the swing arm 132 causes the suction nozzle 131 on a support arm 134 to move toward and away from the spool to suck out the yarn end from the spool.

The cam 69 rotates the forwardly moved slide shaft 110 through levers 135 and 136 cooperating with the sector gear 114. The rotation of the slide shaft 110 causes the empty spool, or core tube, to be removed from the peg N of the winding unit L. Thereafter, said peg is temporarily held horizontal in preparation for the placement thereon of a fresh spool.

The operation of the invention will now be described.

As shown in FIGS. 3 and 9, the carriage 21 fully loaded with spools 28 is moved onto the positioning means in front of the main apparatus body, and a manual switch (not shown) is pushed, whereupon the heads 11 of the four jack means 13 are moved upwardly to fix the carriage 21 in the predetermined position. Subsequently a start button for operating the lifts

38 and 39 is pressed, whereupon the motor 30 is rotated to cause the lifts 38 and 39 to engage the spool raising frames 27 from below and raise all the spools 28 until the five spools at the top stage are transferred onto the spool holders P of the spool holding line H. When the microswitches 80, 81, 82, 83 and 84 detect and ascertain the completion of the correct positioning of all the five spools 28 onto the spool holders P, said group of switches issue a command for the lifts 38 and 39 to be lowered so that the lifts are lowered while carrying the remaining spools to the predetermined position where they are stopped and wait for the next raising operation of the lifts 38 and 39, which will not take place until the spool holding line H is moved clockwise as viewed in FIG. 1 until empty spool holders P come to lie on the extensions of the axes of the poles 26.

In this condition the yarns of the spools previously fed to the pegs N of the winding units L have been taken up completely or if there are yarn breaks that have occurred during take-up operation, the units L will stop in the predetermined position opposed to the spool feed means J. At this time, the yarn remnant detecting means detects the amount of remnants of yarn of the spools on said units L and decides whether to feed fresh spools and knot yarns together to continue the take-up operation or only to mend such yarn breaks. In cases where the yarn remnant detecting means M selectively orders that fresh spools should be fed to said units L, the solenoid clutch 57 for the spool feed cam shaft 54 to which program cams necessary for spool feed are attached is engaged, followed by the rotation of the knitter cam shaft 55 having incorporated therein program cams necessary for knotting. Further, in cases where the detecting means M selectively orders that the mending of yarn breaks alone should be effected, said knitter cam shaft 55 alone is rotated.

When the detects that it is means M detectsit necessary to feed fresh spools, the solenoid clutch 57 for the spool feed cam shaft 54 shown in FIG. 2 is engaged to rotate said spool feed cam shaft 54. As shown in FIGS. 18, 19 and 21, first, the slide shaft 110 is forwardly moved toward the peg N of the stopped winding unit L by the cam 65 until a projection on the front end thereof is fitted in a recess in the slide shaft 110. Next, a turning movement is imparted to the sector gear 114 by the cam 69 to turn the slide shaft 110 half a complete revolution to displace the peg N to a downwardly directed position, whereby the empty spool or core tube is ejected under its own weight. Alternatively, core tube ejection means (not shown) may be provided for ejecting core tubes without directing the pegs N downwardly. After the ejection of the core tube from the peg N, the cam 64 cooperates with the sector gear 114 to turn said peg N 90° to its horizontal position. Almost simultaneously with the forward movement of the slide shaft 110, the swing arm 118 shown in FIGS. 14-16 begins turning under the action of the cam 66 so that peg R moves toward said peg N while the spool 28 on the spool receiving peg R has the axis thereof turned through 90° by the action of the turning rod 123 turning peg R. The turning of the swing arm 118 is stopped at a position where the axes of the peg N and spool receiving peg R are in alignment with each other. The spool push-out lever 128 is then swung to push the

spool 28 off the peg R to transfer it onto the peg N (see FIG. 22). The swing arm 118, which has thus completed the transfer of the spool 28, is then slowly returned to its original position, followed by the retraction of the slide shaft 110 to its original position. As the slide shaft 110 is returned, the peg N having received a fresh spool 28 is returned to its normal position by the action of a spring. At the time when a microswitch 140 especially provided below the base of said peg N ascertains whether or not the transfer of the spool to the peg N has been correctly effected, the above-mentioned spool feed cam shaft 54 has gone through one complete revolution and the winding unit L is ready to be moved out of its position opposite the spool feed means J. In addition, a command for the movement of the winding unit L to be started is issued from a microswitch (not shown) at the time when the knotter cam shaft 55 has gone through its rotation.

After a core tube ejecting means 141 of the known type having a scissors-shaped gripper adapted to turn around an axis for being closed when it assumes a predetermined angular position and for being opened when it assumes another predetermined angular position removes the empty spool or core tube from the peg N and when the peg N is directed horizontally and a fresh spool 28 is transferred to said peg N, whether or not the transfer of the spool to the peg N of the winding unit L is completed at the time when the peg N has been turned through 45° is determined by the end surface of the spool 28 abutting against and pushing the microswitch 140 disposed below the peg N, whereupon a signal for the next operation is emitted. The electrical circuit shown in FIG. 23 is shown in the condition in which winding units L, where there is a winder of the type having circulating winding units L, or the spools, where there is a winder of the type having circulating spools, are stopped in preparation for a transfer operation and also when the pegs and levers begin to work. A description will be given for a winder of the type having circulating winding units L. MS denotes a switch for detecting the stoppage of the units L. Ry₁ denotes a self-hold relay for the feed of spools and its contacts are shown at Ry_{1a} and Ry_{1b}. A relay Ry₂ provides for starting the circulation of the units L, and its contacts are shown at Ry_{2a}. A relay Ry₃ serves to issue a command for the spool feed cam shaft 54 to be driven. In this condition if a fresh spool 28 is fed to the peg N, the contacts of the microswitch 140 are closed, and since the contacts of the relay Ry₂ are normally closed, the relay Ry₁ is actuated to close the contacts Ry_{1a} and cause Ry_{1b} to be shifted to the left-hand contact, with the result that the relay Ry₂ is energized whereas the relay Ry₃ for driving the spool feed cam shaft becomes deenergized so that the rotation of the spool feed cam shaft 54 is stopped. On the other hand, when the winding units L begin to circulate, the contacts of the microswitch 140 are opened and the relays Ry₁, Ry₂ and Ry₃ are deenergized. In cases where the feed of spools is not effected correctly, the microswitch 140 will not be closed and hence the circulation of the winding units L will not be rendered possible. Thus the relay Ry₃ is maintained in its actuated state and the spool feed cam shaft 54 continues its rotation for continuously pushing the spool onto the peg N until the spool is perfectly fed.

When the spool feed cam shaft 54 is rotated, the sprocket wheel 76 is also rotated from the shaft 54 through bevel gears 60 and 70, sprocket 72, chain 74, crank 73 and Geneva wheel 75. The drive train between the shaft 54 and the Geneva wheel 75 is arranged such that the Geneva wheel 75 is rotated one tooth pitch thereof for each complete rotation of the spool feed cam shaft 54 so that the sprocket wheel 76 and hence the carrier chains 79 are moved by an amount corresponding to one pitch of the spool holders P to cause the successive spools 28 to assume a position above the swing arm 118.

When the swing arm 118 completes the feed of the spool 28 and is returned to its original position, the cam 64 causes the rod 103 and lever 104 to turn the presser lever 107 so that as shown in FIG. 17 the upper end of the spool holder P is pressed by the presser lever 107 to release the spool 28, which thereby falls onto the peg R of the swing arm 118 and is fitted thereon. Upon the completion of this falling, the suction pipe 133 shown in FIG. 20 is turned by the action of the cam 68 to bring the suction nozzle 131 into close proximity to the spool 28 fitted on the peg R of the swing arm 118 to draw out the yarn end, and they are returned to their original positions to be ready for the next operation.

Further, immediately after completion of the feed of the spool to the peg N of the winder from the swing arm 118 by the rotation of the spool feed cam shaft 54, the microswitch 137 for the knotting operation command becomes ON to energize the solenoid clutch 56 so that the knotter cam shaft 55 begins to rotate. And the knotting between the yarn end of the cheese being formed at the winding unit L and the yarn end drawn out by the suction nozzle 131 from said fresh spool 28 is effected by a known cam mechanism.

In cases where said detecting means M issues a command that the mending of a yarn break alone be effected, only the solenoid clutch 56 for the knotter cam shaft 55 is energized so that only the knotting between the yarn end from the cheese at the winding unit and the yarn end from the spool on the peg N is effected. In addition, the cam 62 on the spool feed cam shaft 54 serves to actuate the program self-hold microswitch 138. In order to re-energize the solenoid clutch 57 for the knotting cam shaft 55 in cases where the first knotting operation is unsuccessful, whether the requirement set out by the yarn remnant detecting means M is to effect knitting after the feed of a fresh spool or simply knitting, the microswitch is turned ON in advance in preparation for re-actuation in the case of unsuccessful knotting. Further, the cam 61 on the spool feed cam shaft 54 serves to actuate the microswitch 139.

The microswitch 84 at the left-hand extremity in FIG. 2 detects when as the spool holders P holding the spools 28 over the carriage 21 are successively moved to the left as viewed in FIG. 1, the trailing spool holder P holding its spool P has finally passed away from above the poles 26 on the carriage 21. At the command of said microswitch 84 the lifts are moved upwardly, the time of upward movement being determined by the cam 61 actuating the microswitch 139.

In FIG. 11, a circuit is shown in which with no spool 28 on the spool holders P, spools 28 are transferred onto poles 26 and the lifts 38 and 39 are at their lower-

most position with the switch cam 43 pushing the microswitch 45. In practice, however, contacts MS45 are OFF. In this circuit, when a start button PB is pushed, since the microswitches 80, 81, 82, 83 and 84 are mechanically held ON in their normal conditions as shown in FIG. 13 so that the normally opened contacts MS4a, MS4b, MS4c, MS4d and MS4e are closed and the upward movement controlling microswitch 44 is closed, a relay R₁ is energized to close normally opened contacts R_{1a}, R_{1b} and R_{1c}. When the contacts R_{1a} are closed, a self-hold circuit is formed, so that even if the start button PB is released, the relay R₁ will not become inoperative. When the contacts R_{1b} are closed, a magnet switch MGS2 is actuated to change over its contacts MGS2a. At the same time, since the contacts R_{1c} are closed, a magnet switch MGS1 and its contacts MGS1a are closed. As a result, the motor 31 is forwardly rotated to start the upward movement of the lifts 38 and 39. Simultaneously with the upward movement of the lifts, the microswitch 45 becomes OFF so that the contacts MS45 are closed. Subsequently, the five spools 28 are transferred onto the spool holders P and, in the order in which they are correctly transferred, they successively push the microswitches 80, 81, 82, 83 and 84 to open their contacts. If one or more of these spools are not correctly positioned, one or more of the contacts MS42, 4b, 4c, 4d and 4e remain closed, so that the relay R₁ will not be deenergized and the lifts 38 and 39 continue to move upwardly to try to transfer the spools. When all the spools 28 are correctly positioned on the holders P, the contacts MS4a, 4b, 4c, 4d and 4e are opened to cut off the relay R₁ so that the contacts R_{1a}, R_{1b} and R_{1c} are opened. Therefore, the magnet switch MGS2 is cut off to change over the contacts MGS2a. Although the contacts R_{1c} are opened, since the microswitch 45 is OFF, its contacts remain closed and the contacts MGS1a of the magnet switch MGS1 remain closed, so that the motor 30 is reversely rotated whereby the lifts 38 and 39 are lowered and push the counter microswitch 46 and then the downward movement controlling microswitch 45. The contacts MS45 of the microswitch 45 are opened so that the contacts MGS1a of the magnet switch MGS1 are opened to stop the rotation of the motor 30. If the spools 28 on the poles 26 have run out and the lifts are moved upwardly, the switch cam 43 on the lift 39 pushes the upward movement controlling microswitch 44 to change over the contacts MS44 so that a circuit including a pilot lamp and buzzer (not shown) is completed to inform the operator that the spools have run out.

As will be understood from the above, the command for the lifts 38 and 39 to be moved upwardly is given by the manual button the first time and by the microswitch 84 at subsequent times. The timing is provided by the program cam 61 that actuates the microswitch 139. The fact that all the spools held on the poles 26 of the spool supply means F have been transferred to the spool holding line H is recorded on a counter (not shown) by the counter microswitch 46 that counts the number of upward and downward movements of the lifts 38 and 39. If the supply of fresh spools is effected either by the replacement of the carriage 21 or by the circulation of the poles 26 before the five spools transferred last from the spool supply means F are moved to

the feed means J, the transfer of spools can be automatically continued by the microswitch 84.

As has been described so far, according to the present invention, spools properly arranged and held by poles by the use of inner surfaces of the spool core tubes are transferred and fed from spool supply means F to spool holding line H and then from the latter to the pegs N of an automatic winder through spool feed means J, all on the basis of the inner surface of the core tube of such spool, while ascertaining whether or not the spools are correctly received and delivered. Therefore, the transfer and feed of spools can be reliably carried out. Further, since the inner surfaces of the core tubes are exclusively employed for the reception and delivery of spools and the subsequent transfer thereof, there is no possibility of the yarn layers of the spools being contacted by other bodies, thus avoiding damage to and contamination of the outer layers of the spools, and even if the spools have different in the outer diameters, they can be transferred and fed without any trouble.

What is claimed is:

1. An automatic spool feeding method for automatic winders comprising the steps of aligning a plurality of spools each having a hollow bobbin and yarn wound thereon by placing the hollow bobbins onto at least one upstanding pole, moving an individual spool off the pole and transferring the spool to a spool holder which engages the internal surface of the hollow bobbin for holding the bobbin and causing the thus transferred spool to be held by the spool holder, then moving said spool holder to a position adjacent a peg of a spool feed means onto which the hollow bobbin can be positioned, then releasing the engagement of the spool holder with the hollow bobbin and transferring the thus released spool onto said peg, then moving said peg to a position adjacent to a peg of an automatic winder onto which the hollow bobbin can be positioned, and transferring the spool onto said peg of the automatic winder.
2. An automatic spool feeding method as claimed in claim 1 further comprising detecting whether the spool has been properly positioned on the spool holder, and stopping at least temporarily the carrying out of the subsequent steps if the spool has not been properly positioned on the spool holder.

3. An automatic spool feeding apparatus for automatic winders comprising a spool aligning and holding means having at least one upstanding pole, a spool holding means having a plurality of uniformly spaced spool holders each including means for engaging the internal surface of a hollow bobbin of a spool for holding the spool, and spool circulating means for successively circulating said spool holders along a path at one point along which the spool holders are successively aligned with said pole, a spool transfer means having a lift movable upwardly and downwardly adjacent said pole for transferring the spools individually from said pole to a spool holder on said spool holding means, and a spool feed means having a transfer peg movable between a spool receiving position adjacent a second point on said path and a spool delivering position, and spool moving means operatively associated with said transfer peg for transferring the spool from the transfer peg to a peg of an automatic winder at said spool delivering position.

4. An automatic spool feeding apparatus as claimed in claim 3 in which the spool aligning and holding means is a carriage having the pole disposed thereon, said carriage being movable between the position in which the pole is at said one point on said path and a spool loading position.

5. An automatic spool feeding apparatus as claimed in claim 3 in which said spool feed means comprises a swing arm pivoted for movement in a plane perpendicular to the axis of the peg of the automatic winder when said peg is in the spool receiving position, a peg carrier having the transfer peg thereon mounted on one end of the swing arm for rotation in a plane perpendicular to the direction of movement of said one end of the swing arm, means coupled to said swing arm for pivoting the swing arm between a spool receiving position, whereat the transfer peg receives the spool from the spool holder and a delivery position whereat the

transfer peg delivers the spool to the peg of the automatic winder, and means coupled to said peg carrier and responsive to the pivoting of the swing arm toward said delivery position for turning the peg carrier to bring the transfer peg into the delivering position thereof whereat the transfer peg is in alignment with the peg of the automatic winder, and in which said spool moving means comprises a push-out arm pivotably mounted relative to the swing arm for pivotal movement in a plane perpendicular to the direction of movement of said swing arm, and means coupled to said push-out arm for pivoting the push-out arm toward the peg of the automatic winder when the swing arm has arrived at said delivery position to push the spool from the transfer peg to the peg of the automatic winder.
